APPARATUS AND PROCESS FOR MARKING PAPER.

1,187,765.

Specification of Letters Patent. Patented June 20, 1916.

Application filed May 18, 1914. Serial No. 839,272.

To all whom it may concern:

Be it known that we, JOHN B. MORIN, a citizen of the Dominion of Canada, and FRANK O. SCOTT, a citizen of the United States, residing at Mittineague, county of Hampden, and State of Massachusetts, have invented new and useful Improvements in Apparatus and Processes for Marking Paper, of which the following is a specification.

10 This invention relates to a means for applying a mark to paper.

An object of the invention is to provide a marking device or attachment of the kind above alluded to, structurally independent 15 of a paper making machine, but capable of being applied thereto and operating in connection therewith to treat the paper in a certain stage of the process of its formation.

Another object of the invention is to provide 20 a marking device for paper adapted to produce a pattern on the paper of a size larger than the circumference of any roll acting upon the paper in the progress of the letter through the paper treating machine.

25 Another object of this invention is to provide a marking device of the class described, capable of being applied in a suitable machine to treat specially prepared paper.

Another object of this invention is to provide 30 a device of the kind described operable in connection with, but structurally independent of press rolls in paper making or paper treating machines, whereby the device may be applied in connection with the ordinary form of smooth press rolls and requires no special roll or modification of the structure of the machine.

Another object of this invention is to provide 40 a flexible strip adapted to travel through the bite of press rolls along with the paper and thus impart its impress to the paper.

Another object of the invention is to provide 45 a device of the class described, inexpensive to make, simple and efficient in its operation and capable of being easily replaced when damaged.

A still further object of the invention is to provide 50 in connection with the marking device for paper and coöperable therewith, a means whereby the said device may be positively, accurately and readily localized with respect to the material it is adapted to treat.

55 Our invention contemplates the provision

of a pair of pressure rolls or equivalent device, preferably acting upon the paper, if the device is applied in a paper making machine, between the beginning and the end of the drying operation, that is to say when the paper is damp but not wet; and in connection with these rolls a traveling belt adapted to travel through the bite of the rolls with the paper. The invention may be applied, however, in a machine adapted to 65 treat manufactured paper—the operation of the mechanism disclosed herein depending solely upon the condition of the paper and not upon the manner in which the paper attained that condition.

The specific modification of the invention disclosed in the drawings which illustrate the application thereof in one of its simplest forms, relates to a means for causing an impression to be made upon paper rolls while 75 the latter is in a predetermined condition in order to produce a relatively thin stripe in the paper to serve as a hinge in ledger sheets or other analogous purposes.

In the drawings: Figure 1 is a side elevation of an embodiment of our invention shown as applied to a paper making machine. Fig. 2 is a sectional end view of the invention. Fig. 3 is a sectional end view taken on line 3—3 of Fig. 1. Fig. 4 is a 80 detail illustrating the operation of the compression device according to our invention.

In the drawings A represents in general the frame of a paper making machine. In the frame are journaled drier rolls 1 and 2, these rolls being of any well known form and representing any two of the rolls of the series used in such machines. Mounted upon the frame A are standards 3 having therein the vertical extensions 4. The standards 3 are provided with slots such as 5 for the accommodation of the vertically adjustable by means of the bolts 7 and carry journaled therein a lower press roll 8. Journaled in sliding bearings 9 between the vertical extensions 4 is an upper press roll 10. Bolted to the tops of the vertical extensions 4 are the cross bars 11, each provided with an enlarged portion adapted to fit between the vertical extensions 4 and carrying at one end the uprights 12. Threaded through the cross bars 11 are shafts 13 provided at their lower end with blocks 14 adapted to bear upon the sliding bearings 9,

adjacent their upper ends with hand wheels 15 and at their upper ends with shoes 16. Pivoted in the uprights 12 are pressure arms 17 supported in the shoes 16 and carrying at 5 their outer end and adjustable therealong, the weights 18.

Removably bolted to the frame A are the standards 19 in which is a journaled and idler roll 20. In the specific modification of 10 the invention herein disclosed, which relates to a device for making loose leaf ledger sheets having a thin hinged portion, we provide a pair of belts 21, preferably made of steel, which are trained over the upper 15 press rolls 10 and the idler roll 20.

Extending sidewise from the standards 3 are brackets 22, one of which has a projecting ear 23. Slidably mounted in aligned apertures in the brackets 22 is a rod 24 having at one end a plate 25 carrying the block 26 in which is swiveled the end of the hand screw 27 operated by hand wheel 28. The rod 24 has fixed thereon in the specific form illustrated in the drawings, two collars 29 20 carrying arms 30 provided at their ends with eyes 31 encircling the upper and lower reaches of the belts 21. By the mechanism just described the belts 21 may be shifted longitudinally of or held in adjusted position 25 relative to the rolls.

The upper and lower press rolls 8 and 10 are geared together, as shown in Fig. 3 and are positively driven by means of the clutch 32, gear 33 and driving gear 34, these parts 30 being of well known occurrence in the art.

In operation the paper P in its course through the machine passes first about one drier roll then between the press rolls and then about another. In passing between the 40 press rolls 8 and 10 it receives the impress of the belts 21, the paper therefore being compressed in a strip or strips along the line of these belts as shown in somewhat exaggerated form in Fig. 4. Inasmuch as these 45 pressure devices act upon the paper while it is partly, but before it is completely dry, the belts 21 will serve to compress a portion of the already formed paper without tearing apart the fibers or making an indistinct or smudgy impress. Immediately after the 50 action of the compression belts 21, the paper is preferably passed about another drier and the impress thoroughly baked in.

The invention has been shown as applied 55 to a paper making machine. However it may be applied upon a special machine adapted to treat paper which has been dampened in order to get it into the right condition, instead of paper in the course of its 60 manufacture.

It will be clearly understood that belts, such as 21 of other materials than steel may, if desired, be used, steel or some other hard 65 resilient material being, however, in our opinion, preferable. Moreover any number

of belts may be applied, and of any width up to the length of the press rolls. The length of the belts applied and therefore the length of the impression surface which will be impressed upon the paper before a repeat, 70 is of course an arbitrary matter.

We have shown the idler roll 20 as mounted upon the framework of the machine close to the standards 3, but the idler rolls 20 or, if necessary, several idlers and supporting 75 rolls might be availed of and the traveling belt be of any length desired. It would also be possible to provide standards such as 19 at the opposite sides of the standards 3 and make the belt travel completely through the 80 press rolls, and over any number of other rolls, before returning thereto. Finally the impression surface of the belt or belts, such as 21 may carry a design to be imparted to the paper.

While we have illustrated and described one embodiment of our invention as a device for compressing paper in a stripe or strip such as is used in a loose leaf ledger hinge, we wish it to be particularly understood that 90 the invention is by no means limited thereto. One of its important features is the fact that by using an endless belt as the impression surface or die, we make the impression surface practically as large as we desire, thus 95 by providing a belt of this character and placing a design upon its surface (as is well known in connection with marking plates as shown for instance in the patent to Brown No. 1,014,635, dated January 100 16th, 1912) we may impart to the paper a pattern quite independent in its length of the circumference of any roll treating the paper in the course of its progress through the machine, or a set of small patterns of any 105 size, the set being, if necessary, much longer than the circumference of any roll treating the paper in its progress through the machine, whereby a considerable length of paper is impressed before it is necessary to 110 repeat the design. We consider this broadly new.

We claim:—

1. In a paper making machine, means to partially dry the paper, means to finish the 115 drying thereof, a support for the paper interposed between said means, a pressure roll adapted to bear upon the support, a pressure device structurally independent of said pressure roll and interposed between the latter 120 and the support and adapted to travel with the paper, means to adjust said pressure device laterally of the paper.

2. In apparatus of the class described, a support, a pair of rolls journaled in the 125 support, yielding means to cause said rolls to approach each other, another support, an idler journaled in the second support, a flexible belt traveling over one of said rolls and said idler, a rod threading said belt, 130

eyelets supported on the rod for engaging the upper and lower reaches of the belt and manually operable means for longitudinally adjusting the rod.

5 3. In a paper treating machine, a pair of squeezing rolls adapted to have the paper pass therebetween, a flexible metallic pressure device adapted to pass between the compression surfaces of said rolls with the 10 paper, and means to shift said device axially of the rolls or maintain it in adjusted axial position.

4. In a paper making machine, a pair of driers, a pair of squeezing rolls located between the driers between which the paper is caused to pass, a traveling strip having a hard impression means to force said rolls together with a heavy pressure adapted to travel through the bite of the rolls with the 15 paper whereby the impress of the strip is first communicated to the partly dry paper and thereafter rendered permanent.

5. In a paper making machine, a plurality of driers, a pair of squeezing rolls located intermediate adjacent driers, a pressure device relatively movable with respect to either of said squeezing rolls and adapted to travel therebetween in contact with the 20 paper, means to accurately adjust the pressure device axially of the rolls, whereby the 25 paper

impress of the pressure device is communicated to the paper and thereafter baked in.

6. In a paper treating machine, driers for the paper, squeezing rolls located between adjacent driers, an idler roll, an endless tape 35 traveling over one of said squeezing rolls and said idler roll whereby a compressed strip equal in width to the width of the tape is formed in the partly dried paper and thereafter rendered permanent. 40

7. In a paper treating machine, a hard backing roll, a hard pressure roll, yielding means to force the pressure roll against the backing roll with a heavy regulable pressure, a plurality of endless flexible metal 45 bands traveling through the bite of said rolls with damp paper so as to impress said paper, and idler rolls to support said flexible metal bands at points removed from said pressure backing rolls substantially as 500 described.

In witness whereof, we hereunto subscribe our names to this specification in the presence of two witnesses.

JOHN B. MORIN.
FRANK O. SCOTT.
